REFRIGERATOR CAR AND METHOD OF
REFRIGERATION

Robert D. Pike, Pittsburgh, Pa.

Application April 8, 1947, Serial No. 740,117

7 Claims. (Cl. 62—91.5)

1

The present invention relates to a cooling system for a railroad refrigerator car and a method of cooling a refrigerator car, and more particularly to a cooling system and method in which refrigeration is provided by sublimation of solid carbon dioxide, or Dry Ice and assisted by water ice.

An object of the present invention is to provide a railroad refrigerator car that can be charged with Dry Ice and water ice at one terminal and which will be refrigerated for a considerable period solely by the sublimation of the Dry Ice and after the Dry Ice is sublimed, refrigeration will be accomplished by water ice.

Another object of the invention is to provide a railroad refrigerator car in which refrigeration is accomplished by sublimation of Dry Ice, means being provided to control the rate of sublimation whereby the temperature in the car can be controlled to maintain that desired.

A still further object of the invention is to provide a method of refrigerating a car by which Dry Ice may be used and after this ice is sublimed, water ice will be available for further refrigeration.

Other objects and advantages of the invention will be apparent from the following description of a preferred form of the invention, reference being made to the accompanying drawings, wherein:

Fig. 1 is a longitudinal section view of a railroad refrigerator car, the car being shown more or less diagrammatically, and certain elements of the temperature control system are omitted:

Fig. 2 is a view in section taken on line 2—2 of Fig. 1;

Fig. 3 is a view in section taken on line 3—3 of Fig. 1; and

Fig. 4 is a schematic illustration of the temperature control mechanism for the railroad car.

Referring to the drawings, I have shown an insulated railroad refrigerator car 10, suitable for the transportation of food stuffs, for example, at desired refrigerating temperatures. The car includes a relatively large food storage compartment 11, the walls of which are well insulated in the usual manner. At opposite ends of the car, partitions 12 are provided, which with the ends of the car, form vertically extending air cooling chambers 13 at each end of the car. The partitions 12 terminate short of the upper and lower walls of the car to form inlet and outlet openings 14 and 15, for the chambers 13 at the lower and upper portions of the compartment 11, respectively. Preferably, a rack 17 is

2

mounted six inches or so above the bottom of the car and it forms a perforated floor for the compartment 11, so that air may be withdrawn from beneath the rack 17 through openings 14 and circulated upwardly through the chambers 13 and back into the compartment through openings 15. Fans 20 are provided adjacent the inlets 14 for forcefully circulating the air as described, and these fans may be driven from the car axles when the car is moving and driven by electric motors when the car is stationary.

A Dry Ice bunker 22 is located in the lower portion of each of the chambers 13, and each bunker includes a metallic bottom wall 23 which projects outwardly from the lower edge of the partition 12 and parallel to the floor of the car and approximately six inches above the floor. Preferably, the wall 23 extends the entire width of the car and it terminates short of the end wall 24 of the car to allow air to pass upwardly between the end wall of the car and an end wall of the bunker. The wall 23 may be made of 10 gauge sheet steel and the Dry Ice rests directly on this wall so that heat is transferred to the Dry Ice principally to the bottom thereof through the wall. It will be noted that the air entering the compartments will flow in contact with the wall 23. The end wall 24 of the bunker 22 is formed of insulating material as are the side walls 26 and top wall 27. Preferably, these walls are lined with sheet metal, and a sheet metal wall 28 is attached to the end wall 24 and is integral with wall 23 so that heat will be conducted to wall 23, through wall 28. It will be noted that the walls 23 and 28, constitute walls of an air passage upwardly through the chambers 13 and that heat will be transferred from the air to these walls. The top of the bunkers 22 slope downwardly from the partition 12, toward the near end of the car to provide for drainage of melted water ice, as will be brought out as the description proceeds. Dry Ice is loaded in the bunkers 22 through two doorways in each bunker formed in the partition 12. These doorways are normally closed by insulating doors 29. The lower portions of the partitions 12 forming the inner walls of the bunkers 22 are preferably insulated.

Mounted above the bunkers 22 and extending transversely of each of the air passageways 13 is a grill or rack 30, which is adapted to support water ice. The racks 30 are perforated so that air passing upwardly through the chambers 13 will travel upwardly through the ice supported on the rack. The top of the car is provided with

access openings 31, through which water ice is loaded on the racks 30. The openings are adapted to be closed by insulated covers 32.

I propose to control the temperature in the compartment 11 by increasing and decreasing the volume of air passing in heat exchange relation with the walls 23 and 28. One way of effecting such control is shown in which a plate or board 35 of insulating material is provided beneath each wall 23, which boards extend parallel to the respective walls 23 and which may be raised and lowered relative to the walls 23 to decrease and increase, respectively, the cross sectional area of the air passageways between the walls 23 and boards 35. The boards are movable toward and away from the walls 23 by pistons 36, which reciprocate in pneumatic cylinders 31, mounted in the bottom of the car. Likewise, the effective cross sectional area of the air passageways in heat exchange relation with walls 28 can be varied by insulation boards 38 that are moved toward and away from walls 28 by pistons 39 operating in pneumatic cylinders 40 mounted in the end walls of the car. Boards 35 and 38 are substantially coextensive with the respective opposite heat exchange walls. The cylinders 37 and 40 are connected in a common air thermostatically controlled air system to be described presently, so that the boards 35 and 38 will be moved gradually toward and away from their respective heat transfer surfaces simultaneously in accordance with the temperature in compartment 11. In some instances the boards 38 may be omitted.

Referring now to Fig. 4, the control system for the cylinders 31 and 40 is shown schematically, and to simplify the explanation only one cylinder 31, is shown. Air for actuating the piston in the cylinder is supplied from a main pressure tank 45 which may be supplied with air from any suitable source, such as the air line of the train. Air is fed to the upper end of cylinder 31 from the tank 45 through pipes 47, 48 and 49, relay valve 50 and pipe 51. Air is fed to the lower end of cylinder from tank 45 through pipes 47, 48, 49, relay valve 53 and pipe 54. The upper and lower end of the cylinder 31 may be vented to the atmosphere through relay valves 56 and 57, respectively, which are connected to pipes 51 and 54, respectively. To move the piston upwardly for moving board 35 toward the wall 23, the upper part of the cylinder 31 is vented through valve 56 and air is fed to lower end of the cylinder through valve 53. The piston is moved in the opposite direction by venting the lower end of the cylinder and feeding air to the upper end through valve 50.

The relay valves 50, 53, 56 and 57 may be of any well known type that are now available in which a valve member is actuated by a diaphragm, which diaphragm forms a flexible wall of a chamber that is connected with a source of variable pressure. When the pressure on the diaphragm decreases below a predetermined value, the valve opens to permit passage of air through the valve casing and when the pressure on the diaphragm increases, the valve member is closed. The operation of relay valves 50 and 57 is effected by connecting the diaphragm sides of these valves with an auxiliary tank 60, through pipes 61 and 62 respectively, and relay valves 53 and 56 are similarly connected with a second auxiliary tank 63 by pipes 64 and 65, respectively. Thus, the pressure in tank 60 controls opera-

tion of valves 50 and 57 and the pressure in tank 63 controls operation of valves 53 and 56.

The tanks 60 and 63 are connected to the main air tank 45, by pipes 47, 48 and 67. Check valves 58 and 69 are placed in pipe 67 to prevent the flow of air from one tank to the other. Also, gate valves *v*—*v* are located in pipe 48. The main tank thus normally maintains the auxiliary tanks under a predetermined head of air, such as 70 per square inch for example. Preferably, a check valve 70 is located in pipe 47 and this valve is set to deliver air at a relatively slow rate to the cylinders and tanks. The pressure in the auxiliary tanks may be reduced to cause operation of the relay valves in the proper sequence to control the pistons by a thermostatically controlled two way valve, 71. The valve includes a casing having a cylindrical chamber divided by a valve blade or gate 72, pivotally mounted in the chamber at 73. One side of the chamber is connected with tank 60 through pipe 75 and the other side of the valve chamber is connected with tank 63, by pipe 76. Either side of the chamber may be vented to the atmosphere through port 77. When the valve gate 72 is in its normal or intermediate position, as shown in full lines, port 77 is closed and pressure is maintained in both tanks 60 and 63. When valve gate 72 is rotated clockwise to the position shown in dotted lines A, port 77 is opened and tank 60 is vented through pipe 75 and port 77. When the valve gate is rotated in the opposite direction from its normal position, as shown in dotted lines B, tank 63 is vented through pipe 76 and port 77. The valve gate is turned by an arm 78 connected thereto, which arm is normally retained in the position shown in full lines by two oppositely arranged tension springs 80 and 81. One end of the arm 78 is connected to an armature 82 of an electromagnet 83 and the opposite end of the arm is connected to an armature 84 of second electromagnet 85.

The electromagnets are energized by a suitable source of current, such as a dry battery 87. The circuit for magnet 83 includes main switch 88, wire 89, a thermostatic switch 90, wire 91, limit switch 92, wire 93, pressure switch 94, wire 95, to the magnet winding and wires 96 and 97 to the opposite sides of the battery. The circuit for the electromagnet 85 includes wire 89, thermostatic switch 98, wire 100, limit switch 101, wire 102, pressure switch 103, wire 104 to the magnet coil and wire 97 back to the battery.

The thermostatic switch 90 may be any well known commercial type having a bimetal element 106 connected at one end to wire 89, and the opposite end carrying a contact 107. The contact 107 is moved by the bimetal to the left, to engage a fixed contact 108 when the temperature of the bimetal increases above a predetermined value, and it is moved to the right against a fixed contact 109, when the temperature of the bimetal decreases below the predetermined value. The usual means not shown, may be provided for adjusting the bimetal to cause engagement of the contacts at the temperatures desired. The contact 108 is connected to wire 91 and contact 109 is connected to wire 100, so that when the contacts 107 and 108 are engaged the electromagnet 83 will be energized and when contacts 107 and 109 are engaged the electromagnet 85 will be energized, providing the limit switches and pressure switches of the respective circuits are closed.

The limit switch 92 is normally closed and it will be opened by the board 35 when the board

is moved to its position most remote from wall 23. Limit switch 101 is normally closed and it will be opened by the board 35 when the board is against or close to the wall 23. Thus, the limit switches will prevent operation of valve 71 when the control boards 35 are at their extreme positions and the thermostat switch 90 continues to indicate control in the direction in effect. For example, if the thermostat calls for colder air and board 35 is moved to lowermost position, the valve 71 will not be operated until the thermostat calls for warmer air.

Pressure switches 94 and 103 are connected in pipes 75 and 76 respectively, and are arranged to open the circuit therethrough when the pressure in these respective pipes decrease to say 60-50 p. s. i. caused by the opening of valve 71 and they will not reclose the circuits until the air pressure returns to approximately normal.

The thermostatic switch is placed in any suitable location in the food compartment 11, to be sensitive to changes in temperature in the compartment. In the event the temperature increases above that desired, the electromagnet is energized which operates valve 71 to vent tank 60. The decrease in pressure in this tank causes relay valves 56 and 57 to open, admitting air through pipe 51 to the top of cylinder 37 and venting the lower end of the cylinder. This slowly moves the board 35 away from wall 23, thus increasing the air exposed to the wall 23, thereby increasing the rate of heat exchange between the air and Dry Ice. It will be understood that all of the cylinders 37 and 40 will be actuated simultaneously, being connected to pipes 51 and 54 as indicated at the pipes C, so that boards 35 and 38 will be withdrawn from walls 23 and 28. As soon as the tank 60 is vented to some predetermined pressure, usually about 20 p. s. i., below the storage pressure, or to about 50 p. s. i., pressure switch 94 opens the magnet circuit so that valve 71 closes the vent port 77 and bleeding of the pneumatic system will cease with a minimum of loss of air. When the temperature decreases below that desired, electromagnet 85 will be energized to actuate valve 71 to vent tank 63. The reduction in pressure in the tank causes relay valves 53 and 57 to open, admitting air to the lower end of the cylinders 37 and 40 and venting the upper ends. The boards 35 and 38 are thus moved toward their respective heat transfer surfaces to reduce the volume of air passing in contact with the walls 23 and 28 so that the rate of heat exchange between the air and Dry Ice will decrease. When the pressure in tank 63 decreases by about 20 p. s. i., or to about 50 p. s. i., the switch 103 is opened to break the circuit to magnet 85 so that valve 71 closes the vent port 77 and pressure will be restored in tank 63.

After either tank 60 or 63, has been vented to about 50 p. s. i. and the valve 71 has been closed by action of the pressure switches, 94 or 103 opening, as described, the tanks will immediately but slowly begin to recover their pressure of about 70 p. s. i. through the pipe 47 and check valve 68 or 69 respectively, but this pipe and these valves are so proportioned that several minutes will elapse, preferably about 10 minutes, before the pressure in 60 or 63, as the case may be, shall have been restored to the full storage pressure. Also, the valves 94 and 103 are so designed that they will open their switches at about 50 p. s. i. when the pressure is being reduced, but will not close their switches when the pressure is being increased until about 70 p. s. i. Thus, a con-

siderable time lag occurs between deenergizing of one of the relays 83 or 85 by pressure switches 94 or 103, and its re-energizing by the same switch upon restoration of the pressure in tank 60 or 63. 5 This time lag is beneficial in that it minimizes both the use of air and electric current from the battery. When the pressure has been restored in the tank 60 or 63 and the pressure switch which had been open is again closed, the corresponding 10 circuit through relay 83 or 85 again becomes energized and the system is restored to the dictates of the thermostat.

Thus, the pressure switches 94 and 103 cause the boards 35 and 40 to be moved in short steps 15 so that these boards will generally float within the extremities of their range of movement, thereby maintaining an even temperature with a minimum consumption of current and air.

The system shown for moving the control 20 boards 35 and 38 is not necessarily the only one which may be used, but it provides accurate control with a minimum of expenditure of electric current and air pressure. The various control elements may be of conventional design and 25 readily available as commercial products.

In use, the car is loaded at a terminal and prior to loading, the bunkers are filled with Dry 30 Ice blocks and water ice is placed on the racks. Depending on the temperatures to be maintained, salt is added to the water ice, the lower the temperature, the greater the proportion of salt will be used. The thermostat 90 is set to maintain a 35 temperature in the car several degrees below that at which the water ice and salt mixture is capable of producing.

The fans 20 are operated and air is drawn 40 from compartment and circulated upwardly along the walls 23 and 28 of the Dry Ice bunkers, and upwardly through the water ice and then into the upper part of the compartment, as indicated by the arrows. The air cooled by the 45 Dry Ice will maintain the water ice intact since the air will be chilled below the melting point of the ice by the Dry Ice, it being understood that the water ice and salt mixture is adjusted so that its melting point will be a few degrees above the temperature of the air passing from contact with the Dry Ice bunker. After the 50 Dry Ice has been entirely sublimed, the water ice will be available for chilling the air circulated to the compartment 11.

The advantage of my invention is that the 55 car can be charged with a considerable quantity of Dry Ice at most terminals, which ice will provide considerable more refrigeration per pound than water ice. In the event that the Dry Ice is used up before the car reaches its destination, sufficient water ice can be loaded in the car to last for periods of several days. The supply 60 depots of water ice is more wide spread than that of Dry Ice and the supply of water ice is therefore assured.

It will be understood, however, that my invention 65 may be practiced with the entire elimination of water ice and with a corresponding increase in the size of the Dry Ice bunker. In the design shown in the drawings I will ordinarily store at the start, 11,000 pounds Dry Ice and 7500 pounds of the water ice salt mixture. 70 Under usual summer conditions this Dry Ice will last about 8.5 days and the water ice about 2.5 days when using an insulated refrigerator car. This will necessitate a first re-icing in about 10 days as it would not be safe to allow all of the 75 water ice to melt. However, if the water ice be

entirely omitted from my design, additional Dry Ice may be stored to give a running time of about 15 days before the Dry Ice is completely consumed. Either condition represents an immense improvement over present practice when water ice alone is used requiring re-icing every one to two days. If Dry Ice alone were used it would be preferable to install the doors to the Dry Ice bunkers in the sides of the car so that additional Dry Ice could be added before the car was unloaded.

It will be understood that a car could be operated in accordance with my invention but without the use of the insulating boards 35 and 38 and their accompanying automatic controls. However, a car operated in such manner would be uneconomical in the use of Dry Ice because, in order to assure that the car temperature should not rise over 0° F., which is desirable with frozen foods, it will be necessary to ever-refrigerate, subliming Dry Ice at a greater rate than need be and lowering the temperature of the car at times as low as -20° F. This is not only uneconomical in the use of Dry Ice but will also require more frequent re-icing.

The CO₂ from the Dry Ice may be vented to the atmosphere so that it will not enter into the car compartment as is shown at 16.

Although I have described but one form of my invention, it is to be understood that other forms might be adopted, all falling within the scope of the claims which follow.

I claim:

1. A refrigerator comprising a storage compartment; walls forming an air cooling chamber having spaced openings into the compartment to provide an air circulation system through the compartment and chamber; a Dry Ice bunker in the lower portion of the chamber, said bunker having a bottom wall for supporting Dry Ice and forming a heat conductor between air passing therewith and the Dry Ice; an air pervious water ice support in said chamber above the bunker; and means for circulating air from the compartment into the bottom of the chamber and upwardly through the chamber and into the compartment.

2. A refrigerator comprising a storage compartment; walls forming an air cooling chamber having openings into the compartment at the bottom and top of the compartment to provide an air circulation passageway through the chamber to and from the compartment; a Dry Ice bunker in said passageway, said bunker having a bottom wall for supporting Dry Ice and an end wall, said walls forming a heat conductor between the air in the passage and the Dry Ice; an air pervious water ice support in said chamber and extending transversely thereof; and means for circulating air from the compartment through said chamber in a direction to cause the air to pass first in heat exchange relation with said walls of the bunker and then into contact with ice carried by said support and then into the compartment.

3. A refrigerator comprising a storage compartment; walls forming an air cooling chamber having spaced openings into the compartment to provide an air circulating passageway through the chamber; a Dry Ice bunker in the passageway, said bunker having a bottom wall and an end wall forming heat exchange mediums between the air in the passageway and the Dry Ice;

means for circulating air from the storage compartment through the chamber whereby the air passes said walls and then returns to the compartment; two insulating plates in the chamber, one of said plates being substantially coextensive with said bottom wall and the other of said plates being substantially coextensive with the end wall; and means for moving said plates toward and away from the respective walls in response to predetermined temperatures.

4. The method of refrigerating a storage compartment, which consists in circulating air from the storage compartment into heat exchange relation with Dry Ice, then into contact with water ice, and then back to the compartment; and controlling the rate of heat exchange between the air and Dry Ice for maintaining the temperature of the air circulated over the water ice below the melting point of the water ice until the Dry Ice is entirely sublimed.

5. The method of refrigerating a storage compartment, which consists in circulating air from the storage compartment into heat exchange relation with Dry Ice, then into contact with water ice, and then back to the compartment; and controlling the rate of heat exchange between the air and Dry Ice by varying the volume of air flowing into heat exchange relation with the Dry Ice for maintaining the temperature of the air circulated over the water ice below the melting point of the water ice until the Dry Ice is entirely sublimed.

6. A refrigerator car having a storage compartment intermediate the ends and air cooling chambers at the ends, said chambers being connected by openings with the storage compartment at the top and bottom of the chambers; means for circulating air from the compartment through the chambers and back to the compartment; bunkers for containing Dry Ice in the chambers, said bunkers having heat conducting walls for supporting the Dry Ice and being exposed to the air passing through the respective chambers; and a water ice support in each of said chambers and located in the path of air flowing through the respective chambers after passing said walls.

7. The method of refrigerating a storage compartment which consists in circulating air from the storage compartment through a passage, one wall of which forms a heat exchange between the air and Dry Ice; and controlling the rate of heat exchange between the air and Dry Ice by interposing an insulating plate in the passage parallel to said one wall, and moving the plate toward and away from said one wall in accordance with temperature changes in the compartment for varying the depth of the air stream passing in direct contact with said one wall.
